UNITED STATES PATENT OFFICE.

CLARK E. CARR, OF GALESBURG, ILLINOIS.

CAR-COUPING.

SPECIFICATION forming part of Letters Patent No. 290,317, dated December 18, 1883.

Application filed October 5, 1883. (No model.)

To all whom it may concern:

Be it known that I, CLARK E. CARR, a citizen of the United States, residing at Galesburg, in the county of Knox and State of Illinois, have invented certain new and useful Improvements in Car-Couplings; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 My invention relates to railway-car couplings of the ordinary class known as "link-and-pin" couplings; and the objects of my improvements are, first, to furnish means by which the operator may, without going between the cars, hold the link in such position that it will enter the draw-bar head with which a coupling is to be effected, and, second, to afford facilities, without the operator going between the cars, for raising the coupling-pin and holding it in an elevated position both for coupling and uncoupling.

20 The first object of my invention is accomplished by means of a swinging arm provided with a shaft and lever, by means of which it may be raised to lift and hold the coupling-link in position for coupling, and hinged or journaled in such manner that when struck by the adjacent draw-bar, when two draw-bars are brought together for coupling, this link-supporting arm will be driven backward and swing downward and out of the way.

25 The second object of my invention is accomplished by means of a rock-shaft and operating-lever, from which rock-shaft an arm extends and is connected at its outer end with a link or coupling-rod, which link is connected with the coupling-pin in such manner that by turning the shaft the coupling-pin will be raised and tilted backward at its upper end into the ordinary self-sustaining position.

30 A further feature of my invention consists in adapting the same rock-shaft and lever which operates the link-raising arm to also operate the coupling-pin-raising devices, whereby the link may be raised without lifting the pin and the pin raised without lifting the link, all as hereinafter fully described.

In the accompanying drawings, which illustrate one method of applying my improvements to an ordinary car-coupling, Figure 1 is a perspective; Fig. 2, a perspective; Fig. 3, a side elevation, partly in section; Fig. 4, a side elevation; Fig. 5, a side elevation showing the parts in different relative positions from that shown at Fig. 4; Fig. 6, partly a sectional elevation and partly a side elevation, showing the parts in same relative positions as shown at Fig. 5; Fig. 7, a perspective of the link-lifting arm; Fig. 8, a side elevation of the link-lifting arm and section of rock-shaft; Fig. 9, a detail figure hereinafter referred to.

35 Referring to the drawings by letters, the same letter indicating the same part in the different figures, A represents a portion of one end of a car; B, a draw-bar; C, a coupling-link, and D a coupling-pin. The parts B C D constitute an ordinary link-and-pin coupling, and need not be any more fully herein described, as their manner of operation is well known.

40 E is a rock-shaft located transversely to and beneath the end of the car, and journaled in any suitable pendants, e, and provided at each of its ends, beyond the side of the car, with a hand-lever, e', (only one of which is shown.)

45 F are arms loosely seated on the shaft E—one at each side of the draw-bar. Each arm F has a slot, f, through which a pin, f', passes, to secure the arm F from movement endwise of said shaft, while it permits limited rotation of the shaft without movement of said arm, and moves the arms F with the shaft when the pin comes in contact with the end of the slot. Each arm F has a link or connecting-rod, G, 50 hinged or journaled at its lower end to the outer end of said arm, and these links G are connected at their upper ends by a rod, g, which passes through a hole in the upper end of the coupling-pin D. Each arm F is bent 55 upwardly and outwardly at its outer end to form a dog, f''. When the coupling-pin is seated in the draw-bar, the normal positions of the dogs f'' are, as shown most plainly at Fig. 2, not in contact with the links G; but when the shaft E is turned to raise the links G, and after they and the coupling-pin have been raised a short distance, these dogs will come, respectively, in contact with said arms G and

force them rearward as the shaft E is further turned, and thereby incline the coupling-pin rearwardly at its upper end, in which position its lower end will rest in the upper end 5 of the hole through the draw-bar, so as to sustain it, as shown most plainly at draw-bar B' in Fig. 6, as is commonly done in coupling cars, and in such manner that when the draw-bars come in contact in coupling, the elevated 10 coupling-pin will be thrown forward at its upper end by the jar, and will then drop into its seat in the draw-bar.

H is the swinging link-lifter, having a slot, h, at one end, one end, h', of which slot 15 is enlarged, and the other end, h'', contracted. A flattened portion, e'', of the shaft E passes through the slot h. The flattened portion e'' of the shaft is of such size in its cross-section relatively to the slot h that it 20 can only enter the contracted part h'' of said slot when presented edgewise of its flattened portion thereto, as shown most plainly at Fig. 9, while the portion h' of the slot will admit the portion e'' of the shaft, with its broader 25 way transverse to the slot, as shown most plainly at Fig. 8. The outer or forward end, h'', of the lifter H is turned upwardly and made broad, so that it will sustain the link, as hereinafter described.

30 For convenience in describing the operations of my car-coupling, I will further designate one of the draw-bars by the accented letter B', and will assume that two draw-bars are already coupled, as shown at Fig. 3. While 35 the draw-bars are coupled, and in fact at all times while the coupling-pin is in its vertical position in the draw-bar, the normal position of the link-lifter H is vertical, as shown at Fig. 3, and the flattened portion e'' of the shaft

40 E rests in the enlarged part h' of the slot h, while the lever e' also stands in its normal position, designated by the letter e' with a figure 1 after it, to indicate the first position of said lever, as shown at same figure. To uncouple, 45 one of the coupling-pins may be raised by turning the lever e' to the position shown by a figure 2 after its reference-letter e', to designate its second position, as shown at Fig. 4. In turning the lever e', and with it the shaft 50 E, as last described, the flattened portion e'' of the shaft will rotate in the enlarged part of the slot h, and hence not move the link-lifter H. To effect a coupling, one of the coupling-pins is raised to its elevated position, as last de- 55 scribed for uncoupling, (see draw-head B' at Figs. 5 and 6,) where it is sustained by the inclined position of the coupling pin in the hole in the draw-head, as also hereinbefore described. The lever e' of the draw-head B is 60 then turned up to its third position—designated by a figure 3 after its reference-letter e'—which turns the shaft E so that its flattened portion e'' permits the link-lifter H to fall to a lower plane, and thus bring the portion e'' 65 of the shaft into the contracted portion h'' of the slot, as shown by dotted lines at Fig. 3,

when, by turning the lever e' downward to its fourth position, (shown at Figs. 2, 5, and 6,) the rotation of the shaft e' will raise the link-lifter and hold the link C in the elevated position at 70 its outer end, (shown at same figures,) in which position it will enter the draw-head B' as the two draw-heads are brought together. As the draw-heads approach each other, and after the link enters the head B', the head B' will strike the 75 outer end of the lifter H, and, driving it backward, as shown by dotted lines at Fig. 6, the slot h will slide on the shaft E until the flattened portion of said shaft is in the enlarged part of the slot, when the lifter H will fall to its normal 80 position, (shown by broken lines at same figure,) and the jar of the draw-heads or bumpers coming together will drop the elevated coupling-pin, as hereinbefore described, and thus effect the coupling.

85 The use of the slot f and pin f' may be described as follows: When the lever e' is in its first position, the pin f' will be near the rear end of the slot f, as shown at Figs. 1 and 2, and hence as the shaft E is turned rearwardly 90 the pin in contact with the rear end of the slot will raise the arms F and coupling-pin, as hereinbefore described. The slot f will also permit turning the shaft E in the opposite direction from that last described without mov- 95 ing the arms F, when said shaft is so turned backward to allow the link-lifter to fall to a lower plane, so that it may be swung upwardly, as hereinbefore described.

100 By means of this invention an operator may couple and uncouple cars in which any ordinary "link and pin" is used without going between the cars.

105 What I claim as new, and desire to secure by Letters Patent, is—

1. In a car-coupling, in combination with a draw-bar, link and pin, and a rock-shaft, E, provided with means for operating it, the link-lifter H, connected to the rock-shaft at one end, so as to swing with it, and its other end adapted to act directly on the link, substantially as and for the purpose specified.

2. In a car-coupling, in combination with an ordinary draw-bar, link and pin, and a rock-shaft, E, provided with means for operating it, a link-lifter, H, having a slot, h, enlarged at one end to rotate on the shaft E, and contracted at its other end, whereby the shaft may raise it to support the link, substantially as and for the purpose specified.

115 3. In a car-coupling, in combination with a draw-bar, link and pin, and a rock-shaft provided with means for operating it, a link-lifter connected with said rock-shaft by a sliding connection, whereby it may slide backward 120 in coupling the cars, and may slide outward on the shaft to permit raising it by means of the shaft, substantially as and for the purpose specified.

4. In a car-coupling, in combination with the rock-shaft E, having a flattened portion, e'', the link-lifter H, having a slot, h, with an

enlarged portion, h' , and contracted portion h'' , substantially as and for the purpose specified.

5. In a car-coupling, in combination with an ordinary draw-bar, link and pin, and a rock-shaft, E, the arms F and G and rod g, adapted to raise the coupling-pin by rotating the shaft E, and the arms F, provided with the dogs f'', for inclining the pin as it is elevated, substantially as and for the purpose specified.

6. In a car-coupling, in combination with a rock-shaft, E, and slotted link-lifter H, adapted to slide and swing on the shaft E, substantially as described, the arms F and G and rod g, adapted to raise the coupling-pin, substantially as and for the purpose specified.

15 7. In combination with the shaft E and

swinging link-lifter H, the arms F and G and rod g, substantially as and for the purpose specified.

8. In combination with the shaft E, slotted link-lifter H, arms G, and rod g, the arms F, having slots f, which receive the pins f', substantially as and for the purpose specified.

9. In combination with the shaft E, slotted link-lifter H, arms G, and rod g, the arms F, having dogs f'' on their outer ends, substantially as and for the purpose specified.

In testimony whereof I affix my signature in presence of two witnesses.
